UNITED STATES PATENT OFFICE.

HUGH McCABE, OF LAWRENCE, MASSACHUSETTS, ASSIGNOR TO McCABE MANUFACTURING COMPANY, OF LAWRENCE, MASSACHUSETTS, A PARTNERSHIP.

LOCOMOTIVE BOILER.

Application filed August 17, 1926. Serial No. 129,760.

The present invention relates to an improvement in locomotive boilers.

The fire box of locomotive boilers is subject to wide fluctuations of temperature due to the variations in fire necessarily incident to making steam under the varying conditions demanded by service, and owing to banking of the fires which lowers the temperature still more. As a result of these fluctuations in temperature the fire box is subjected to serious variations of stresses. The fire box is well braced to stand the pressure of the steam, but when the temperature falls the metal contracts, and when it rises the metal expands, and the changes of dimensions incident to this cause severe stresses to be exerted upon the portions of the fire box subjected to the greatest variation in temperature, and particularly to the corners. It is the practice to fillet the sides of the fire boxes to avoid sharp corners, but in the case of a tube sheet this is obviously a matter of such difficulty that it has not been attempted. The tube sheet is ordinarily provided with a flange at its edge to which the sides of the fire box are riveted, and the corner between the tube sheet and its flange is subjected to the severest stresses, and ordinarily the tube sheet requires replacement from time to time.

The lap joint where the sides of the fire box lap over the flange of the tube sheet presents a thickness of metal about double the thickness of the fire box plates, and according to the present invention it is proposed to thicken the tube sheet at the flange corner so as thereby to strengthen it at the place where it commonly gives out first. The object of the invention is to improve the locomotive boiler by producing a more durable tube sheet, and to this end the invention consists in the tube sheet for locomotive boilers hereinafter described and particularly defined in the claim.

In the accompanying drawings illustrating the preferred form of the invention, Fig. 1 is a longitudinal section of a boiler illustrating the fire box provided with the tube sheet of the present invention; Fig. 2 represents the joint between the side plates and tube sheet of the fire box on an enlarged scale, taken on the line 2-2, Fig. 3; and Fig. 3 is a front elevation of the tube sheet, the tube holes being omitted.

The illustrated embodiment of the inven-

tion is described as follows: The boiler 1 is provided with a fire box 2 supported in place therein in the usual manner. The fire box comprises the side sheets 3 and the tube sheet 4. The tube sheet consists of a plate 60 of metal of the thickness desired for the fire box, having a thicker portion 5 at the angle between the plate and the flange 6. The tube sheet is made of metal of the thickness of the corners 5, and flanged by any usual or 65 convenient method, preferably cold flanged, as this method of flanging secures greatest strength of metal. After the sheet is formed the portion 7, indicated within the dotted lines, is milled out, and the portion 70 8 of the sheet is also milled out, leaving the flange 6 and sheet 4 of the desired thickness. It will be observed that when the side sheets 3 of the fire box are riveted to the flange 6 of the tube sheet, the metal of the double 75 layer will have a thickness approximately equal to the thickness of the corner of the flange, so that the portion of the fire box extending from the inner end of the box around to the corner of the tube sheet to the 80 tube sheet itself will be of substantially uniform thickness.

When the fire box is heated to the high temperature incident to use, the joint between the inner edges of the side sheets and the flange of the tube sheet, and the corner of the tube sheet being of substantially the same thickness, will equalize and distribute the strains throughout this large mass of metal, and thereby tend to secure a more 90 equable distribution of stresses. So also when the fire box cools again, the stresses will be distributed throughout this cold mass of metal, and will not be localized at the corner between the tube sheet and its 95 flange as heretofore, with the result that the tube sheet will have much longer life than the tube sheet heretofore employed.

Having thus described the invention, what is claimed is:

A tube sheet for fire boxes of locomotives having a tube sheet proper formed with a flange at its edges, the angle between the tube sheet and the flange being thicker than the tube sheet proper to enable it to bear the stresses of expansion and contraction due to fluctuations in the temperature.

In testimony whereof I have signed my name to this specification.

HUGH McCABE.
